UNITED STATES PATENT OFFICE.

NEWTON R. CARRELL, OF DECATUR, ALABAMA.

SHOE-NAIL.

1,257,807.

Specification of Letters Patent. Patented Feb. 26, 1918.

Application filed August 25, 1917. Serial No. 188,135.

To all whom it may concern:

Be it known that I, NEWTON R. CARRELL, a citizen of the United States, residing at Decatur, in the county of Morgan and State 5 of Alabama, have invented new and useful Improvements in Shoe-Nails, of which the following is a specification.

This invention is an improved shoe nail for use on the sole or heel of a shoe to protect the same from wear, the object of the invention being to provide an improved nail of this character which embodies a shank and a head so constructed that the shank holds the nail in place when driven into a 10 sole or heel and the head readily enters the leather, displaces only a minimum quantity of the leather and serves to firmly hold the portions of the leather between the head and the heads of adjacent nails.

20 The invention consists in the construction and arrangement of devices hereinafter described and claimed.

In the accompanying drawings:—

Figure 1 is a perspective view on an enlarged scale of a shoe nail constructed and arranged in accordance with my invention.

Fig. 2 is a side elevation of the same.

Fig. 3 is an end elevation of the same.

Fig. 4 is a plan of the same.

30 Fig. 5 is a plan of a sole and heel of a shoe and showing the arrangement of my improved nails therein to protect the same.

Fig. 6 is a sectional view of the same on the plane indicated by the line 5—5 of 35 Fig. 4.

My improved shoe nail comprises a shank 1 and a head 2. The sides of the shank are parallel with each other and the shank is provided with a broad chisel-like entering 40 point 3 which may be readily driven into the leather of a sole or heel and the shank, owing to the parallel arrangement of its

sides is securely retained in place in the leather.

The head 2 extends laterally from one of 45 the broader sides of the shank and is of substantially oblong rectangular form in plan, with a rounded outer end 4. Cross-sectionally the head is triangular and is formed with downwardly converging longitudinal 50 sides 5 which form an edge 6 on the under side of and which extends longitudinally of the head.

This construction of the head enables the same to be readily driven into the leather 55 of a sole or heel, the head, owing to its wedge-shaped cross-section, readily entering the leather and displacing the same only to a minimum extent. The head may be readily driven into the leather until its outer 60 surface is flush with the surface of the sole or heel so that the nail forms no obstruction or unevenness whatever on the sole or heel and greatly promotes the comfort of the user of the shoe. In practice my nails are 65 applied to the sole or heel at a slight distance apart, as shown, and, owing to the wedge-shaped cross-section of the heads of the nails the leather between the heads is firmly held, like the key-stone of an arch. 70

Having thus described my invention, I claim:—

The herein described shoe nail comprising a shank and a head, said shank having parallel sides and a broad chisel-like entering point and said head extending laterally from the shank and being wedge-shaped in cross-section to provide an entering edge on the lower side and arranged longitudinally thereof, said entering edge of the head 75 being arranged at right-angles to the chisel-like point of the shank.

In testimony whereof I affix my signature.
NEWTON R. CARRELL.
